CONTAINER CLOSURE

Paul Norris, Ardmore, Pa., assignor of forty-five
one hundredths to Ralph McKittrick, Villa-
nova, Pa.

Application November 10, 1933, Serial No. 697,490

2 Claims. (Cl. 221—60)

This invention relates to new and useful improvements in closures for containers and more particularly to closures for collapsible tubes such as are used in dispensing tooth paste, glue, shaving cream, medicinal compounds and like substances.

The principal object of the invention is to provide a closure for containers of the character set forth having means operative to permit easy manipulation thereof by the thumb or finger of the hand holding said container.

Another object of the invention is to provide a device of the stated character which may be manufactured at relatively small expense and offered for sale as an individual article of merchandise, or which may be substituted for the customary screw cap by the manufacturers and vendors of the container or its contents.

A more specific object of the invention is to provide a device of the character described including a resilient sliding member operable to insure a tight closure of the opening in the receptacle when not in use.

Other features and objects of the invention and the details of construction thereof are set forth more fully hereinafter and shown in the accompanying drawing, in which:

Fig. 1 is a view in section of the cap member or closure contemplated by the present invention associated with the discharge end of a collapsible tube.

Fig. 2 is a view in perspective of the cap member contemplated by this invention.

Fig. 3 is a view in perspective of the sliding member which has been removed from the cap, and

Fig. 4 is a view in elevation of a modified form of the closure member.

The invention is particularly desirable with regard to tubes containing shaving cream, dentifrice, or like substances, as it permits the tube to be held in one hand, the discharge aperture being opened by the thumb thereof, the other hand being free to hold a shaving brush, tooth brush, or other article to which the substance within the tube is to be applied.

Referring now more particularly to the drawing, a closure cap made in accordance with this invention comprises a cap-like structure designated generally as 1 having a circular sleeve 2 threaded internally as at 3 for engagement with corresponding threads 3a formed externally of the discharge port 4 of a container 5, the diameter of said sleeve 2 and the size of its threads 3a depending respectively upon the size of the port

4 of said container 5 and the threads 3a formed thereon.

In the present instance a web 6 having an aperture 7 therein in alignment with the opening of the port 4 extends over the upper end of the sleeve 2. Side walls 8 extend upwardly from the longitudinal edges of said web, and as shown in Fig. 2 the upper edge of each side wall 8 is bent or turned inwardly as at 9, so that they extend toward each other and reside in a plane parallel to the plane of the web 6. The side walls 8 and the inwardly formed upper edges 9 constitute guide ways for a sliding closure member which is described more in detail hereinafter.

In the present instance one end of the web 6 extends laterally beyond the end of the side walls 8 as at 10 and constitutes a platform-like support, said web 6 and its extension 10 being coplanar with one another as shown in the drawing.

A closure member or blade 11 is slidably retained on the web 6 by means of the guide ways or runners formed by the side walls 8 and the inwardly projecting portions 9. Preferably the closure member 11 is made of a strip of spring steel or other resilient metal, which is bent double as shown in Fig. 3, in order that the lower arm 12a thereof will be forced against the web 6 and more perfectly seal the opening 7 therein to prevent discharge from the tube. The extremity or free end of the upper arm 12b of the closure member 11 is formed to provide an abutment 13 for engagement by the thumb or finger of a person holding the tube so that said member 11 may be readily moved longitudinally of the cap 1.

For the purpose of retaining the sliding closure member 11 at all times longitudinally within the bracket or cap the extreme edge of the laterally extending portion 10 of the web 6 is bent upwardly to form a stop 14 and the other end edge of the web 6 is bent upwardly to form a stop 15 at the other end of said cap.

A modification of the closure member 11 is shown in Fig. 4 of the drawing and comprises upper and lower arms 12a and 12b as previously described together with the thumb engaging portion 13. However it will be noticed that a forwardly projecting tongue 16 is formed co-planar with the lower arm 12a at the bend or fold in the strip 11 and extends a small distance therebeyond. The tongue 16 functions to shear the excess substance discharged from the tube or container from the cap and maintain the surface of the web 6 and the guideways substantially clean at all times.

It has been stated that the member 11 is pref-

erably formed from a spring steel or other resilient strip and in addition it is pointed out that the cap, including the sleeve 2, web 6 and guide ways constitute an integral structure which preferably is molded "bakelite" or other hard fibrous or rubber composition, or the same may be fabricated of metal as desired.

While a specific embodiment of the invention has been set forth for purposes of description it is not intended that the same be specifically limited thereto within the scope of the appended claims.

What is claimed is:

- 15 1. A closure for containers comprising an integral sleeve element adapted to be threaded on to the discharge neck of a container, said sleeve including a top portion provided with an opening therein aligned with the discharge port of the container, side walls extending from opposite sides of said top portion, flanges extending inwardly from said side walls in spaced relation with respect to the top portion to form parallel undercut grooves, a projection extending laterally of said sleeve beyond the ends of said side walls in the plane of the top portion, a doubled resilient closure element slidable on said top portion and in the grooves formed by the flanges, said flanges engaging the surface of the upper arm 20 of said doubled resilient closure element and compressing the element firmly against the top portion, and means at the extremity of said projection arranged to engage the lower free end of said closure element to prevent displacement 25 thereof from said sleeve element.

gaging the upper surface of said resilient closure element and compressing the same firmly against the top portion, and means at the extremity of said projection to prevent displacement of said closure from the sleeve element.

2. A closure for containers comprising an integral sleeve element adapted to be threaded on to the discharge neck of a container, said sleeve including a top portion provided with an opening therein aligned with the discharge port of the container, side walls extending from opposite sides of said top portion, flanges extending inwardly from said side walls in spaced relation with respect to the top portion to form parallel undercut grooves, a projection extending laterally of said sleeve beyond the ends of said side walls in the plane of the top portion, a doubled resilient closure element slidable on said top portion and in the grooves formed by the flanges, said flanges engaging the surface of the upper arm 20 of said doubled resilient closure element and compressing the element firmly against the top portion, and means at the extremity of said projection arranged to engage the lower free end of said closure element to prevent displacement 25 thereof from said sleeve element.

PAUL NORRIS.
